UNITED STATES PATENT OFFICE.

WATSON B. STOCKMAN AND JOHN F. FRIEL, OF CHESTER, PENNSYLVANIA.

LAMP-BURNER ATTACHMENT.

SPECIFICATION forming part of Letters Patent No. 748,889, dated January 5, 1904.

Application filed May 15, 1903. Serial No. 157,296. (No model.)

To all whom it may concern:

Be it known that we, WATSON B. STOCKMAN and JOHN F. FRIEL, citizens of the United States, residing at Chester, in the county of Delaware and State of Pennsylvania, have invented certain new and useful Improvements in Lamp-Burner Attachments, of which the following is a specification.

This invention provides a simple attachment for the ordinary form of oil-lamp burners for extinguishing the flame after the wick has been lowered or in case of accident to instantly extinguish the flame though the wick be turned up to its fullest extent.

The attachment is adapted for application to the type of burners aforesaid which are in use or may be applied to them when placed upon the market.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a perspective view of the burner, parts broken away. Fig. 2 is a vertical sectional view showing more clearly the operation between the presser-bar and the extinguishing-sleeve which surrounds the wick-tube. Fig. 3 is a perspective view of the presser-bar removed.

Corresponding and like parts are referred to in the following description and indicated in all the views of the drawings by the same reference characters.

The attachment contemplates the provision of a hollow wick-shaft 1, which is applied to the burner 2 as usual and which is provided with the spur-wheels 3, by which the wick is operated. The burner-cap 4 also is illustrated, and the finger-piece 5 of the wick-raising shaft 1 will also be seen to be of the type commonly employed for this purpose. The hollow wick-receiving shaft 1 receives a reciprocating bar 6, which constitutes what will be termed a "spring-retraction" presser-bar. The presser-bar is provided at its in-

ner end with a bent portion or inclined engaging part 7, which co-operates with the sleeve 8 to extinguish the flame when this becomes necessary. The sleeve 8 is preferably of tubular form, though any other suitable means of analogous character may be substituted for the same within the sphere of our invention. The presser-bar 6 is provided at its outer end with a finger-piece 9, by which same is manipulated. Between the finger-piece 9 and the finger-piece 5 of the shaft 1 is interposed a coil-spring 10, which is disposed about the bar 6 and serves to hold the presser-bar normally in an outmost position. The finger-piece 9 of the presser-bar is preferably revoluble, so that should same be seized by mistake for the purpose of raising or lowering the wick no damage will be suffered by the attachment. Projected from the lower portion of the sleeve 8 is an extension 11, which extension covers a lateral lug 12. This lug is inclined and co-operates with the inclined portion 7 of the presser-bar to raise the sleeve 8 when it is desired to extinguish the flame. The presser-bar 6 is guided in its movement by a pair of lugs 13, disposed upon the base of the burner, which lugs engage the presser-bar upon either side of the upturned end portion thereof and serve to prevent any lateral movement of the inclined end 7, so that this inclined end is assured a movement which will also cause co-operation with the lug 12, projected from the extension 11 of the extinguisher-sleeve. This is deemed of some importance to the practical embodiment of the invention.

In the operation of the attachment to extinguish the flame, the presser-bar being in its outermost position, it is but necessary to exert a pressure upon the finger-piece 9 to force the presser-bar 6 inward. This causes the inclined end portion of the said bar to ride into engagement with the lug 12, this movement causing subsequent vertical movement of the extinguisher-sleeve 8. Removal of the pressure upon the finger-piece 9 permits same to resume its normal position under the influence of the spring 10 in a manner which will be readily apparent.

The attachment involves a decided simplicity relative to the number of parts used, and consequently the cost of manufacture is

reduced to the smallest degree consistent with proper material and other considerations.

Having thus described the invention, what is claimed as new is—

5. 1. In an attachment of the class described, the combination with a lamp-burner, of a wick-tube, a spring-retracted presser-bar disposed for reciprocal movement upon the burner, an inclined engaging portion disposed upon the presser-bar, extinguishing means disposed adjacent the wick-tube aforesaid, and means extended from the aforesaid extinguishing means adapted for coöperation 15 with the inclined portion upon the presser-bar whereby the flame may be extinguished.
10. 2. In an attachment of the class described, the combination with a burner, of a hollow wick-raising shaft disposed thereon, a spring- 20 retracted presser-bar disposed for reciprocal movement within the wick-raising shaft, an inclined engaging part disposed upon the presser-bar, guide means coöperating with the presser-bar to direct the movement of the 25 aforesaid inclined portion, and an extinguishing-sleeve disposed adjacent the wick-tube and coöperating with the inclined portion of the presser-bar.

3. In an attachment for burners and the like, the combination with a sleeve disposed adjacent the wick-tube, a hollow wick-raising shaft, a spring-retracted presser-bar disposed within the shaft for reciprocal movement, an extension projected from the extinguishing-sleeve aforesaid, and an inclined 35 engaging part provided upon the presser-bar for engagement with the aforesaid extension and for actuation of the sleeve by such engagement.

4. In an attachment for burners and the like, the combination with a wick-tube, an extinguishing-sleeve disposed about the said tube having a lug projected therefrom, a hollow wick-raising shaft, a spring-retracted presser-bar disposed for reciprocal movement within the said shaft and having its inner end bent upward to form an inclined 45 engaging portion for coöperation with the lug projected from the extinguishing-sleeve.

In testimony whereof we affix our signatures in presence of two witnesses.
